United States Patent Office.

WILLIAM WESTLAKE, OF BROOKLYN, NEW YORK.

Letters Patent No. 76,867, dated April 7, 1868.

IMPROVEMENT IN THE MANUFACTURE OF SPOUTS FOR TEA-POTS.

The Schedule referred to in these Letters Patent and making part of the same.

TO ALL WHOM IT MAY CONCERN:

Be it known that I, WILLIAM WESTLAKE, of the city of Brooklyn, in the county of Kings, and State of New York, have invented certain new and useful Improvements in the Manufacture of Spouts for Tea-Kettles; and I do hereby declare that the following is a full, clear, and exact description of the same, reference being had to the accompanying drawings, making a part of this specification, in which—

Figure 1 represents an inside view of the spout as swaged ready for putting together.

Figure 2, a complete spout formed from the form shown in fig. 1; and

Figure 3, a transverse section of fig. 1.

Like letters refer to the same parts in all of the figures.

Heretofore, in the construction of bent spouts made of sheet metal, the sides or sections have been swaged separately, or of two separate pieces, and soldered together, forming two seams the entire length of the spout, which not only increased their liability to leak, but also increased the cost of manufacture. My invention consists in swaging the spouts from a single piece of metal, so as to form them nearly their entire length with but one seam.

To enable others skilled in the art to make and use my spouts in my improved method, I will describe the same.

The tin or other sheet metal which is to be manufactured, is cut into proper sizes for the size and length of the spout to be made, and swaged in the form shown at fig. 1, the sides A and A', each forming one-half of the spout, and a ridge, B, formed between them, except when they are bent or curved. The piece is cut at E, so that when the sides are brought together, the proper angle or incline will be given to the spout when attached to the tea-pot or kettle. The upper end is also cut so as to form the proper curve, and a small piece of metal, D, is left so as to prevent, when the sides are brought together, the formation of a hole at the commencement of the curve. When properly swaged, the metal is bent at B, and the edges c brought together; the point D attached to A', is turned under A, and from that point to the end the edges are soldered as at c. By leaving the point D at the commencement of the curve, the formation of a hole will be prevented when the parts are lapped over each other for soldering purposes. These spouts when formed are attached in the usual manner.

It will be obvious that handles for coffee-pots, tea-pots, and other articles, can be made in the manner herein described for making spouts.

Having thus fully described my invention, what I claim as new, and desire to secure by Letters Patent, is—

The method herein described of forming curved or bent spouts of a single piece of sheet metal, substantially as specified.

WILLIAM WESTLAKE.
